(57) CLAIM

The ornamental design for a shelving unit, as shown and described.

DESCRIPTION

FIG. 1 is a front, right side, top perspective view of a shelving unit embodying my new design;

FIG. 2 is a rear, left side, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged front, right side, top perspective view of the portion labeled "9" in FIG. 1.

The dot dash lines illustrate the bounds of the enlarged view and form no part of the claimed design.

1 Claim, 6 Drawing Sheets
